UNITED STATES PATENT OFFICE.

JAY B. RHODES, OF HARVEY, ILLINOIS, ASSIGNOR TO FREDERICK C. AUSTIN, OF CHICAGO, ILLINOIS.

STREET-SPRINKLER.

SPECIFICATION forming part of Letters Patent No. 636,846, dated November 14, 1899.

Application filed July 5, 1898. Serial No. 685,192. (No model.)

To all whom it may concern:

Be it known that I, JAY B. RHODES, a citizen of the United States, residing at Harvey, in the county of Cook and State of Illinois, 5 have invented a certain new and useful Improvement in Street-Sprinklers, of which the following is a specification.

My invention relates to street-sprinklers of that class in which a hollow sprinkler-head 10 is arranged to receive the water from a tank or receptacle on the cart or wagon and is provided with a laterally-apertured cap-sleeve having a sliding connection with the hollow 15 sprinkler-head and adapted to discharge the water through its apertured side when it is projected from the sprinkler-head to an extent to expose its apertured side.

Prominent objects of my invention are to provide a simple, compact, and highly-efficient 20 construction, to vary the volume of the water discharged and to vary the direction of the discharge in a simple and reliable manner, to effectively avoid leakage and all undesirable drip of water from the sprinkler-head at such times as the discharge is cut off, 25 to provide a construction and arrangement whereby a packing employed to prevent leakage can be adjusted or crowded up in a way to compensate for such wear as might tend to 30 permit leakage, and to permit the sprinkler-head to be flushed when so desired.

To the attainment of the foregoing and other useful ends, the laterally-apertured sprinkler-cap sleeve is arranged to receive 35 and slide upon an open-end portion of the hollow sprinkler-head, so that when projected therefrom it will provide a laterally-apertured chamber, which receives the water from the hollow sprinkler-head and discharges the 40 same through its apertured side. By this arrangement the laterally-apertured side of the sprinkler-sleeve will be closed when it is over the outer side of the hollow sprinkler-head and opened when it is moved out of register 45 therewith. By arranging the sprinkler-cap sleeve to receive and slide over the open-end portion of the hollow sprinkler-head I am also enabled to provide packing which while serving to effectively prevent leakage is also covered and protected by the sprinkler-cap sleeve, and which, as hereinafter set forth, can

also be adjusted with reference to such wear as may otherwise permit objectionable leakage and waste of water. As a further simple and desirable arrangement the sprinkler-cap 55 sleeve is operated by a rod which is supported by and extended longitudinally through the hollow sprinkler-head, such arrangement also permitting the sprinkler-cap sleeve to be rotatably adjusted, when so desired, in an easy 60 and convenient way.

In the accompanying drawings, Figure 1 represents in side elevation a sprinkler cart or wagon with my improved sprinkler device. Fig. 2 is a rear elevation of Fig. 1. Fig. 3 65 shows the tank, driver's seat, and treadle in front elevation. Fig. 4 is a section taken longitudinally and centrally through one of the sprinkler-heads and adjuncts on a larger scale than in the preceding figures. Fig. 5 shows 70 the sprinkler-cap sleeve in central longitudinal section and a portion of the hollow sprinkler-head in side elevation. Fig. 6 is a cross-section on line *xx* in Fig. 5. Fig. 7 is a cross-section on line *yy* in Fig. 4.

The sprinkler cart or wagon may be of any ordinary or approved construction and is provided, as is usual, with a suitable water tank or reservoir A. This vehicle is desirably provided with a couple of sprinkler devices, 80 respectively arranged at opposite sides of its rear end portion and adapted to discharge the water transversely to the line of progression of the vehicle and in rear of the rear wheels thereof.

Each sprinkler device comprises a hollow sprinkler-head B, which is in open communication with the water-tank through the medium of a lateral pipe or duct C. The form of the sprinkler-head may be varied without departing from my invention, it being preferable, however, to adopt a cylindric or substantially cylindric shape.

The sprinkler-head is provided with a longitudinally-sliding sprinkler-cap sleeve D, 95 adapted and arranged to receive the rear end portion of the sprinkler-head and fitted to slide longitudinally thereon for the purpose of establishing and cutting off the discharge of water at will. The sprinkler-cap sleeve is 100 formed with a cylindric body portion *d* and a closed rear end *d'* and has its cylindric body

portion fitted to slide upon the rear end portion of the sprinkler-head, it being understood that as a matter of course the form of such body portion of the sprinkler-cap sleeve 5 in cross-section could be modified with reference to any change in form of the sprinkler-head.

The sprinkler-cap sleeve can be moved forwardly or retracted on the sprinkler-head in 10 order to cut off the discharge, and it can also be moved rearwardly for the purpose of establishing the discharge in quantity proportional to the extent to which it is projected back from the sprinkler-head. When the 15 sprinkler-cap sleeve is projected back from the sprinkler-head, it serves, in effect, to rearwardly extend the latter, and at such time it also forms a chamber which receives the water from the sprinkler-head preparatory to 20 discharging the fluid onto the street. To permit such ultimate discharge of the water, the body portion of the sprinkler-cap sleeve is laterally apertured either by perforations d^2 or by transversely slotting it. When the 25 sprinkler-cap sleeve is retracted or moved forward upon the sprinkler-head, as in Fig. 4, its apertured portion will be brought over and closed by an imperforate portion of the sprinkler-head, which latter, broadly considered, 30 may be understood to comprise the sprinkler-head proper and certain adjuncts or fixtures thereon hereinafter described. When the sprinkler-cap sleeve is moved back or projected from the sprinkler-head, as in 35 Fig. 5, it will receive water from the sprinkler-head and discharge the same in volume proportional to the extent to which its apertured portion is opened, in which way the volume of the discharge can be readily regulated by 40 the device employed for longitudinally adjusting the sprinkler-cap sleeve upon the sprinkler-head. As a simple and efficient device for thus longitudinally adjusting the 45 sprinkler-cap sleeve a rod or pitman E is extended longitudinally through the sprinkler-head and attached to the closed end of the 50 sprinkler-cap sleeve, the forward end of this rod being connected with suitable operating means—for example, a swinging hanger or lever F, attached to the vehicle and connected by a rod G with a lever or treadle H, located at the forward end of the vehicle in position to be operated by the driver. With 55 such arrangement the sprinkler-head serves to guide and support and partially inclose the longitudinally-movable rod E. To prevent leakage, the rod can work through suitably-arranged packing or a stuffing-box I at the forward end of the sprinkler-head, and to 60 further guide and support the rod it may also work through a bearing b, arranged within the rear portion of the sprinkler-head.

A further advantage involved in the foregoing-described construction resides in the 65 fact that while the sprinkler-cap sleeve can in an extremely simple way be adjusted longitudinally for the purpose of establishing,

varying, and cutting off the discharge it can also be rotatively adjusted for the purpose of varying the extent to which the water is 70 thrown laterally from the vehicle. To such end the rear terminal portion of the adjusting-rod E extends through a corresponding opening in the closed end of the sprinkler-cap sleeve and is threaded to receive a clamp-nut K, which latter can be tightened up to rigidly clamp the sprinkler-cap sleeve against a shoulder on the rod and also loosened to permit the sprinkler-cap sleeve to be turned about the axis of the rod to any desired extent, the nut after such adjustment on the 80 part of the sprinkler-cap sleeve being of course again tightened up against the latter, so as to secure it upon the rod. In this way I provide the sprinkler-head with an apertured cap-sleeve adapted for both longitudinal and rotary adjustment, so as to meet all 85 sprinkling requirements, and, further, I provide extremely simple means for effecting and permitting such adjustments. The rod E 90 could of course be connected with the lever F by a swivel-joint, in which case the sprinkler-cap sleeve could be adjustably turned by turning the rod; but as a preferred and simpler arrangement the sprinkler-cap sleeve 95 is adjustably attached to the rod and the latter connected with the lever by a sliding pivotal joint having sufficient play to compensate for the swing of the lever.

As a matter of further improvement the 100 sprinkler-head comprises a hollow body portion having as an adjunct or fixture thereon a separately-made clamping piece or plate L, consisting of an apertured disk or plate which is arranged opposite and secured to the rear 105 end of the hollow body portion of the sprinkler-head by bolts M. This construction permits an annular packing P to be clamped between the clamping-plate L and the rear end of the hollow body portion of the sprinkler-head as a means for effectively guarding 110 against leakage of water between the peripheral surface of the body portion of the sprinkler-head and the body portion of the sprinkler-cap sleeve which slides thereon, it being observed that the packing thus employed 115 is arranged to attain such end. A further advantage attending such arrangement is that the bolts can be adjusted to clamp the packing between the plate L and the sprinkler-head proper, and hence when the packing or 120 contacting surfaces of the sprinkler-cap sleeve and sprinkler-head become worn as the result of operating the sprinkler-cap sleeve all wear of such parts can be readily compensated for 125 by simply tightening up the bolts to an extent to crowd the packing and cause it to bulge laterally. To insure the result last mentioned, the packing is desirably fitted in an offset either in the clamping-plate or in 130 the rear end of the body portion of the sprinkler-head—as, for example, in the clamping-plate, as illustrated.

The foregoing-described arrangement of

clamping-plate L also permits an annular packing R to be fitted to the inner side of the closed end of the sprinkler-cap sleeve and arranged to seat against the plate L when the 5 sprinkler-cap sleeve is retracted upon the sprinkler-head, as in Fig. 4, thereby further guarding against leakage, particularly when the sprinkler-cap sleeve is apertured to an extent to leave any part of its apertured portion opposite the periphery of the plate L or the packing P when the sprinkler-cap sleeve is retracted upon the sprinkler-head.

As to matters of detail, the plate L can be constructed as a spider having an annular 10 seating portion l for the two packings, a central bearing l' for the adjusting-rod E, and radial arms or web portions l'', adapted to provide bearings for the bolts. With this arrangement the plate L will have segmental-shaped openings l'', through which water from the 15 sprinkler-head proper can pass into the chamber provided by the sprinkler-cap sleeve when the latter is projected from the sprinkler-head. The rear end of the body portion 20 of the sprinkler-head may have a construction similar to the plate L—that is to say, it may have an annular internally-arranged flange providing a seating-surface for the packing P and a central bearing b connected 25 with such flange by arms or web portions b', arranged to leave spaces between them for the free passage of water. In order to flush 30 the sprinkler-head, the rod can be moved back to an extent to cause the sprinkler-cap sleeve 35 to entirely clear the sprinkler-head, and thereby permit a full flow of water.

What I claim as my invention is—

1. The hollow sprinkler-head closed at one 40 end and open at its opposite end, and provided with a suitable inlet; a laterally-apertured sprinkler-cap sleeve closed at one end and arranged to receive and slide longitudinally over the open-end portion of the sprinkler-head, and also adapted to provide, when 45 projected from the sprinkler-head, a laterally-apertured receiving-chamber which receives the water from the sprinkler-head and discharges the same through its apertured side in volume proportional to the extent to 50 which it is thus projected; and a longitudinally-movable adjusting-rod connected with the sprinkler-cap sleeve and extending longitudinally through the sprinkler-head; the apertured side portion of the sprinkler-cap 55 sleeve being closed by an imperforate side portion of the sprinkler-head when brought over the same, and being opened to an extent proportional to the extent to which it leaves the head when it is adjustably projected from 60 the latter.

2. The hollow sprinkler-head closed at one end, and open at its opposite end, and provided with a suitable inlet; a longitudinally-movable rod extending longitudinally through 65 the sprinkler-head and connected with operating means under control of an attendant or driver upon a sprinkler cart or wagon where-

on the sprinkler-head is supported; and a laterally-apertured sprinkler-cap sleeve fitted to receive and slide longitudinally over the open-end portion of the sprinkler-head; the sprinkler-cap sleeve being also fitted to turn upon the sprinkler-head, and having a rotary adjustable connection with the rod which extends through the sprinkler-head, and providing when projected from the sprinkler-head a laterally-apertured chamber which is opened or closed with reference to the discharge therefrom to an extent proportional to the extent to which its apertured side is 80 projected from or retracted over the side of the head.

3. The sprinkler-head constructed with a hollow body portion having a closed end, and an opposite open end; an apertured clamping 85 piece or plate arranged opposite and attached to the open end of the hollow body portion of the sprinkler-head; a packing clamped between said two members; and a longitudinally-adjustable, laterally-apertured sprinkler-cap sleeve, closed at one end and adapted and arranged to receive and slide over the open-end portion of the sprinkler-head, and to provide when projected from the sprinkler-head a laterally-apertured receiving and discharging chamber which is opened proportionally to the extent to which it is projected 90 from the sprinkler-head, and which is at all times packed against leakage by the packing confined between the clamping piece or plate 95 and the open end of the hollow body portion of the sprinkler-head.

4. The sprinkler-head constructed with a hollow body portion having a closed end and an opposite open end; an apertured clamping 105 piece or plate arranged opposite and attached to the open end of the hollow body portion of the sprinkler-head; a packing clamped between said members; a longitudinally-adjustable, laterally-apertured sprinkler-cap 110 sleeve closed at one end and adapted and arranged to receive and slide over the open-end portion of the sprinkler-head, and to discharge through its apertured side when it is projected from the sprinkler-head; and a packing which 115 is clamped between the closed end of the sprinkler-cap sleeve and the apertured clamping piece or plate when the sprinkler-cap sleeve is retracted upon the head to an extent to close its apertured side.

5. The sprinkler-head comprising a hollow body portion having its opposite ends respectively closed and open, and provided at its closed end with a stuffing-box or piston-rod packing; an adjusting-rod extending longitudinally through the hollow body portion of the sprinkler-head and connected with suitable operating means; an apertured clamping piece or plate arranged opposite the open end of the hollow body portion of the sprinkler-head and adjustably bolted thereto; a packing clamped between the clamping piece or plate and the hollow body portion of the sprinkler-head; and a longitudinally-sliding,

rotatably-adjustable, and laterally-apertured sprinkler-cap sleeve fitted to receive and work upon the open-end portion of the sprinkler-head and connected with the adjusting-rod.

5 6. The hollow sprinkler-head having an open-end portion, the laterally-apertured cap-sleeve closed at one end and arranged to slide longitudinally upon the said open-end portion of the hollow sprinkler-head, means for shifting the cap-sleeve so as to open or close the

aperture or apertures in said cap-sleeves, and a packing-ring interposed between the said open end of the sprinkler-head and the end wall of the cap-sleeve, whereby the supply of water may be cut off from the said aperture 15 or apertures in the cap-sleeve.

JAY B. RHODES.
